TROLLEY SHOE CURRENT COLLECTOR

Charles M. Feist, Sioux City, Iowa

Application December 31, 1943, Serial No. 516,404

5 Claims. (Cl. 191—59.1)

My invention pertains to a trolley shoe.

An object of my invention is to provide a trolley shoe which will provide a snug and firm contact with the overhead cable of a trolley line at all times, and regardless of the angle thereof.

A further object of my invention is to provide a shoe of this character which includes an automatic feeding brush which will feed to the contacting area as it becomes necessary without providing too rapid a feeding action or a too slow a feeding action.

A further object of my invention is to provide a brush arrangement which is uniformly fed to the cable along tapered surfaces for the above reasons, and which includes certain interlocking means between the brush members to maintain the brush at the desired level.

A further object of my invention is to provide a shunt contact means to by-pass the resilient springs in the arrangement for the purpose to be described.

A further object of my invention is to provide a rockable shoe, which will rock according to the requirement of angularity of the trolley pole.

A further and important object of my invention is to provide means so that the brushes when worn can be readily replaced without requiring dis-assembly of the entire unit.

A further object of my invention is to provide resilient and automatic features to engage the contacting elements with the overhead cable regardless of shocks, jars, and the like.

A further object of my invention is to provide means for adjusting the tension of the brush members.

A further object of my invention is to provide an easily assembled arrangement which is simple in construction.

With these and other objects in view, my invention consists in the construction, arrangement, and combination of the various parts of my device, whereby the objects contemplated are attained, as hereinafter more fully set forth, pointed out in my claims, and illustrated in the accompanying drawing, in which:

Figure 1 is a sectional view taken substantially along the lines 1—1 of Figure 2, and

Figure 2 is a fragmentary section taken generally along the lines 2—2 of Figure 1.

I have used the character 10 to designate a metal trolley pole, which is suitably attached at the top of a trolley car or similar vehicle, and to which pole 10 is attached the split head comprising the two side members 11 which are adapted to receive the contacting arrangement of my in-

vention. Received within the members 11 are a pair of pins 12 which include the threaded extensions 13 upon which are threadably engaged the nuts 14 received within the cavities 15. The pins 12 are each attached to or formed integrally from the central pin or shaft 16 which shaft 16 is thereby adapted to rock relative to the side members 11.

Attached to the shaft or pin 16 is a tapered member 17 including the tapered sides 18 and spaced from the sides 18 are the further tapered end walls 19 including the tapered surfaces 20 against which surfaces and between the tapered surfaces 18 are placed the contacting brushes 21 which brushes can be made of graphite, carbon, or any other suitable material. The brushes 21 include the opposed interlocking notches 22 which are adapted to nest one within the other as the brush material of the brushes 21 is fed upwardly, and the upper spacing between these notches is very slight, and increases as the notches progress downwardly so that the brushes will be locked together at any vertical movement or position and will thereby not spring out of place and whereby the upper contacting surfaces 23 of the brushes will constantly remain at the lower level of the trolley cable 24.

The spacing between these notches is so graduated so that the brush material will be fed to the upper level and to that level only due to this interlocking arrangement.

In order to feed the brushes 21 upwardly as they are used I provide the members 25 having the cavities 26 through which cavities are placed the pins 27 which are attached to the vertical rods 28 which rods terminate in the heads 29.

I further provide a forcing member 30 including the extending legs 31 under which legs are received the heads 29 and between the members 25 and 31 are positioned the compression springs 32 which receive the annular portions 33 and 34.

A pair of wire leads 35 are suitably connected to the members 25 and are thence connected at 36 to the member 17. The member 30 includes an opening 37 through which is received the rod 38 which is attached at 39 to the member 17 and which is threadably engaged at 40 with the nut 41, this nut being provided to maintain compression against the springs. The side bows 42 include the integral horizontal portions 43 the upper surfaces of which are rounded to conform to the cable 24 and the portion 43 extends into the downwardly projecting angularly positioned flanges 44 which are adapted to be attached against the surfaces 45 which extend from the

walls 19. The machine screws 46 are provided for this purpose, and attached at one side to one of the flanges 44 and against the surface 45 is a flat metal member 48 which is attached to a lead 49 which is attached at 50 to the pole structure.

Also attached to the end walls 19 and to the sides of the portion 48 are a pair of downwardly extending dished portions 51 including the bottom walls 52 and which include the opening at 53 for receiving the aforesaid flange 44. The members 51 include the sides 54 which sides merge flush with the sides of the upper member 42, the portion 54, however, being split apart at 55 from the members 42, so that as a result the members 42, and the portions 43 and 44 are all one unit piece and are separate from the portions 54 and 52. This allows for removal of the upper piece comprising the members 42 etc. It should be noted that the members 43 also include the tapered portions at 56 which are coincident with the tapers 20 for apparent reasons.

The lead 49 is attached to provide a shunt connection so that the current will not pass through the springs 32 thereby maintaining the quality of the springs. The leads 35 and 36 convey the current from the brushes and provide a shunt feature with the contact being also carried through the large pin 16. The members 42 include the arcuate surfaces at 57 which abut against stops 58 (see Figure 2) which are attached to the members 11 to limit angular movement of the entire assembly.

It will be noted from the above description that the entire assembly unit comprising the brushes 21, the housing 19, the members 42, 52, and springs 32, the members 30, 38, and the tapered member 17 will provide a complete composite body and will thereby be pivoted about the pins 12 as a single unit. As the trolley passes along the overhead wire 24 it can then provide a contact regardless of angular position of the pole for this reason and in some cases where the trolley passes over a crossing the pole may be raised to a considerable angle and the device will still function properly.

It will be further noted that the cable contacts the surface 23 of the brushes at all times, due to the pressure of the springs 32. It will be further noted that a contact is applied by the flange 43 thereby providing a constant uniform contacting arrangement, which contact is constantly lubricated with graphite etc., to provide the best type of contact which contact is applied at just the proper pressure, without too great a pressure by virtue of the interlocking arrangement of the brushes.

When the members 42 and flanges 43 are worn, this unit can be quickly detached and replaced, due to the above described split arrangement.

Also the brushes when worn down can be replaced readily by removing the assembly mounted on the nut 41, and it will be noted that the members 25 are rockably mounted on the pins 27 so that the pressure can be uniformly applied against the brushes regardless of the angularity thereof.

From the above description it will be noted that the entire unit will wear a relatively long time and can be readily replaced when worn, and provides a firm and snug contacting arrangement.

It will also be seen that this arrangement provides all of the advantages mentioned in the objects of my invention, other advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A trolley shoe current collector comprising in combination with the end of a trolley pole, a current collector pivotally mounted at the end thereof, said collector including a pair of brushes, and having upwardly converging channels receiving said brushes, means for feeding said brushes upwardly against an overhead trolley wire, including springs bearing against said brushes, a spring retaining member upon which said springs are mounted, said brushes having opposed interlocking serrated surfaces for preventing relative vertical movement of said brushes with respect to each other.
2. A trolley shoe current collector comprising in combination with the end of a trolley pole, a current collector pivotally mounted at the end thereof, said collector including a pair of brushes, and having upwardly converging channels receiving said brushes, means for feeding said brushes upwardly against an overhead trolley wire, including springs bearing against said brushes, a spring retaining member upon which said springs are mounted, said brushes having opposed interlocking serrated surfaces for preventing relative vertical movement of said brushes with respect to each other, spring abutment means mounted on said springs adapted to press against the lower surfaces of said brushes, said spring abutment means being rockably mounted with respect to the springs.
3. A trolley shoe current collector comprising in combination with the end of a trolley pole, a current collector pivotally mounted at the end thereof, said collector including a pair of brushes, and having upwardly converging channels receiving said brushes, means for feeding said brushes upwardly against an overhead trolley wire, including springs bearing against said brushes, a spring retaining member upon which said springs are mounted, said brushes having opposed interlocking serrated surfaces for preventing relative vertical movement of said brushes with respect to each other, spring abutment means mounted on said springs adapted to press against the lower surfaces of said brushes, said spring abutment means being rockably mounted with respect to the springs.
4. A trolley shoe current collector comprising in combination with the end of a trolley pole, a current collector pivotally mounted at the end thereof, said collector including a pair of brushes, and having upwardly converging channels receiving said brushes, means for feeding said brushes upwardly against an overhead trolley wire, including springs bearing against said brushes, a spring retaining member upon which said springs are mounted, said brushes having opposed interlocking serrated surfaces for preventing relative vertical movement of said brushes with respect to each other, spring abutment means mounted on said springs adapted to press against the lower surfaces of said brushes, said spring abutment means being rockably mounted with respect to the springs.
5. A trolley shoe current collector comprising in combination with the end of a trolley pole, a current collector pivotally mounted at the end thereof, said collector including a pair of brushes, and having upwardly converging channels receiving said brushes, means for feeding said brushes upwardly against an overhead trolley wire, including springs bearing against said brushes, a spring retaining member upon which said springs are mounted, said brushes having opposed interlocking serrated surfaces for preventing relative vertical movement of said brushes with respect to each other, spring abutment means mounted on said springs adapted to press against the lower surfaces of said brushes, said spring abutment means being rockably mounted with respect to the springs.

the springs, said serrations normally being slightly separated to provide means whereby said springs will force said brushes upwardly and towards each other upon erosion of the upper surfaces of the brushes, said collector including a centrally positioned member having upwardly converging walls providing portions of said channels, said brushes abutting against said walls.

5. A trolley shoe current collector comprising in combination with the end of a trolley pole, a current collector pivotally mounted at the end thereof, said collector including a pair of brushes, and having upwardly converging channels receiving said brushes, means for feeding said brushes upwardly against an overhead trolley wire, including springs bearing against said brushes, a spring retaining member upon which said springs are mounted, said brushes having opposed inter-

locking serrated surfaces for preventing relative vertical movement of said brushes with respect to each other, spring abutment means mounted on said springs adapted to press against the lower surfaces of said brushes, said spring abutment means being rockably mounted with respect to the springs, said serrations normally being slightly separated to provide means whereby said springs will force said brushes upwardly and towards each other upon erosion of the upper surfaces of the brushes, said collector including a centrally positioned member having upwardly converging walls providing portions of said channels, said brushes abutting against said walls, shunt electrical connections by-passing said springs.

CHARLES M. FEIST.
